(57) **CLAIM**

The ornamental design for a laser processing machine, as shown and described.

DESCRIPTION

FIG. 1 is a front view of a laser processing machine of the present invention;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a front, top and left side perspective view thereof;

FIG. 8 is a rear, bottom and right side perspective view thereof;

FIG. 9 is a sectional view thereof with inner mechanism is omitted taken along the line 9-9 in FIG. 3;

FIG. 10 is an enlarged sectional view thereof with inner mechanism is omitted taken along the line 10-10 in FIG. 3 of the portion defined by the lines 1001-1001 in FIGS. 3 and 1002-1002 in FIG. 6; and,

FIG. 11 is an enlarged view thereof defined by the lines 1101-1101 and 1102-1102 in FIG. 6.

The dash dot dash broken lines define the bounds of the claimed design and form no part thereof.

The broken lines depict portions of a laser processing machine that form no part of the claimed design.

1 Claim, 11 Drawing Sheets
